UNITED STATES PATENT OFFICE

141,791

DESIGN FOR A BRACELET DISPLAY STAND

Fred Siegel, New York, N. Y.

Application March 12, 1945, Serial No. 118,438

Term of patent 7 years

(Cl. D80—9)

To all whom it may concern:

Be it known that I, Fred Siegel, a citizen of the United States of America, residing in New York city, county of Bronx, and State of New York, have invented a new, original, and ornamental Design for a Bracelet Display Stand, of which the following is a specification, reference being had to the accompanying drawing, forming part thereof, wherein,

I claim:

The ornamental design for a bracelet display stand, substantially as shown.

FRED SIEGEL.
